UNITED STATES PATENT OFFICE.

ALEXANDER A. PARKS, OF TALLASSEE, ALABAMA.

DESIGN FOR A HEAD-REST HOLDER FOR BARBERS' CHAIRS.

45,888.

Specification for Design.

Patented June 2, 1914.

Application filed March 31, 1914. Serial No. 828,628. Term of patent 7 years.

To all whom it may concern:

Be it known that I, ALEXANDER A. PARKS, a citizen of the United States, residing at Tallassee, in the county of Elmore and State of Alabama, have invented and produced a new, original, and ornamental Design for Head-Rest Holders for Barbers' Chairs, of which the following is a specification, reference being had to the accompanying drawing, forming a part hereof.

The figure is a perspective view of a head-rest holder showing my new design.

As shown in the drawing the leading or material feature of my design consists of a plate A formed in the shape and representation of a shield and the outstanding loop B,

the outer contour of which is formed in the shape and representation of a heart and having centrally thereof and cut therefrom a portion which leaves the form and representation of a heart.

I claim:

The ornamental design for a head-rest holder for barbers' chairs as herein shown and described.

In testimony whereof I have signed my name in the presence of two subscribing witnesses.

ALEXANDER A. PARKS.
